UNITED STATES PATENT OFFICE.

HUGH DAVISON, OF NEW LONDON, CONNECTICUT, ASSIGNOR OF ONE-HALF TO DAVID J. MCKENNA, OF NEW LONDON, CONNECTICUT.

SELF-CLOSING CAR-FENDER.

1,118,535.

Specification of Letters Patent.

Patented Nov. 24, 1914.

Application filed October 15, 1913. Serial No. 795,279.

To all whom it may concern:

Be it known that I, HUGH DAVISON, a citizen of the United States, residing at New London, county of New London, State 5 of Connecticut, have invented an Improvement in Self-Closing Car-Fenders, of which the following is a specification.

This invention has for its object to provide a fender adapted for attachment to the 10 ends of cable, steam or motor driven cars, which shall be so constructed as to reduce to the minimum the danger of injury to a person struck and which shall be provided with a hinged guard projecting in front of 15 the frame of the fender which is released when a person falls upon the fender and swings upward, so that a person caught by the fender will be retained thereon and the danger of being run over will be greatly 20 reduced.

With these and other objects in view I have devised the novel self-closing fender which I will now describe referring to the 25 accompanying drawing forming a part of this specification and using reference characters to indicate the several parts.

Figure 1 is a plan view of my novel fender with the guard lowered as in use; Fig. 2 a side elevation thereof, Fig. 3 is a 30 section on the line 3—3 in Fig. 1, looking in the direction of the arrows, and Fig. 4 is a front elevation of the apparatus.

The frame 10 of my fender, comprises a vertical portion 10^a and a horizontal portion 35 11^a, the portion 11^a extending under the front platform of a car and attached to the car by any suitable means.

The numeral 11 designates the web of the fender, made of interwoven cords, the edges 40 of the web being secured to upstanding curved arms 12, which are secured to the upper portion of the vertical frame portion 10^a and the forward portion of the horizontal frame portion 11^a. The web 11 extends 45 downwardly from the curved arms 12, and has its forward portion secured to a transverse bar 13', secured to the frame portion 11^a, as shown. At the rear edge, the web 11 extends upwardly, and has its outer portions 50 secured to an upper horizontal bar 15^a, attached to the vertical frame portion 10^a, while the inner portion of the web 11 is secured to a vertically movable bar 14, connected with the bar 15^a by means of 55 springs 15.

The numeral 13 designates sides of an inner frame, which are suitably secured to bar 13' and a rear bar 13^c, below bar 15^a, as more clearly shown in Fig. 3. Within the sides 13 is a vertically movable platform 16, resting upon springs 17, in turn supported upon bars 17^c, which are attached to the arms 13, as is obvious.

The numeral 18 designates a vertically swinging guard, embodying a transverse 65 rod or bar 18^c, rigidly attached to cranks 18', having their rear ends apertured to receive reduced portions 18^a, of bar 19^a. This bar 19^a has its reduced portions 18^d passing through apertures in the horizontal frame 70 portion 11^a, as shown. The forward end of the guard is preferably covered by a rope or cable 26, secured to the crank 18', as shown. This rope is adapted to be engaged by pivoted hooks 25, secured to the arms 12, 75 and which serve to retain the guard in the upper positions when moved thereto. The movement of the guard past the horizontal position is limited by stops 27, secured to the forward ends of the frame portion 11^a, 80 as shown. The guard 18 is moved upwardly by retractable coil springs 24, attached to the crank 18' at 24^a, and to the vertical frame portion 10^a, as at 24^b.

Means are provided to normally lock the 85 guard against upward movement, comprising a lever 21, pivoted upon the bar 13', with its rear end having a loose pivotal connection as at 22, with the platform 16, as shown. The forward end of the lever 21 is 90 provided with a depending hook 19, to enter a loop 23, carried a crank 25^a, to normally prevent the rear end of the crank 25^a from swinging downwardly. The crank 25^a is secured to a bar 18 and the bar 18^c, as 95 shown at 17^a, the forward end of the crank being forked as shown.

The operation is as follows: When the apparatus is ready for use, the guard 18 is set or moved to the horizontal, the cranks 18' 100 engaging stops 27. The hook 19 passes within or engages the loop 23, to hold crank 25^a against movement. The platform 16 is now raised.

When the fender strikes a person, he falls 105 upon the platform 16, forcing the same downwardly. This movement of the platform swings the rear end of the lever 21 downwardly, to withdraw hook 19 from the loop 23. The crank 25^a is now released, 110

whereby the guard 18 is swung to the vertical position to prevent the person from rolling off on the fender in front of the car. It is obvious that the web 11 is so arranged 5 that it will deflect the person upon the table 16. The portion of the web 11 secured to the vertically movable bar 14, is capable of yielding, to prevent undue injury to the person being caught.

10 Having thus described my invention I claim:—

1. In a fender, a web-carrying frame, a vertically swinging guard pivoted to the outer portion of the web-carrying frame, a 15 spring to swing the guard upwardly when released, an element connected with the guard and movable therewith to control its upward movement, a movable member connected with the web-carrying frame and 20 having detachable engagement with the element, a movable platform carried by the web-carrying frame, and means connecting the platform and the movable member.

2. In a fender, a web-carrying frame, an 25 upwardly movable guard arranged near the outer end of the frame, automatic means to move the guard upwardly when released, means to normally lock the guard in the lower position, an element arranged above a 30 portion of the web-carrying frame and adapted to be moved by an object caught by the frame and having operative connection with the lock means, a movable platform carried by the frame and connected with 35 the locking means, and separate automatic means to positively hold the guard in the upper position when moved thereto.

3. In a fender, an approximately horizontal frame, a web connected therewith, a 40 vertically swinging guard pivoted to the outer end of the frame, a spring to swing the guard upwardly, a crank secured to the

guard to move therewith and provided at its free end with a loop, a vertically swinging lever arranged within the frame and 45 provided with a depending hook to enter the loop, a vertically movable platform arranged within the frame, springs interposed between the platform and frame to retain the former elevated, and means connecting 50 the platform and lever.

4. In a fender of the character described, a main frame, a web attached thereto, a vertically swinging guard secured to the forward end of the main frame, stops secured to the main frame to limit the downward movement of the guard, springs to swing the guard upwardly, gravity operated latches to engage the guard when swung to its 55 upper position to lock the same therein, means to normally prevent the upward movement of the guard, and a vertically movable platform connected with the means to operate the same.

5. In a fender, a main frame embodying horizontal and vertical portions, a vertically swinging guard secured to the horizontal portion of the frame, means to swing the guard upwardly, means to control the upward movement of the guard embodying a vertically movable member arranged upon the horizontal portion of the frame, a section of web arranged behind the platform, a bar to which the upper portion of the web is secured, and springs connecting the bar with the upper portion of the vertical portion of the frame.

In testimony whereof I affix my signature in presence of two witnesses.

HUGH DAVISON.
